UNITED STATES PATENT OFFICE.

CHARLES G. ERICSON, OF TORONTO, ONTARIO, CANADA.

RAIL ANCHOR.

Application filed May 24, 1922. Serial No. 563,895.

To all whom it may concern:

Be it known that I, CHARLES G. ERICSON, of the city of Toronto, in the county of York, Province of Ontario, Canada, a subject of the King of Great Britain, have invented certain new and useful Improvements in Rail Anchors, of which the following is a specification.

This invention relates to rail anchors of the type shown and described in my prior United States Patent No. 1,402,852, dated Jan. 10th, 1922, in which there is employed a jaw member adapted to embrace one edge of a rail base and having its back formed as a wedge, and a yoke member having a hook at one end adapted to engage one edge of a rail base and a hook at the other end embracing the jaw member and overhanging the rail base, the engaging surfaces of the jaw member and the upper part of said hook sloping inwardly and downwardly in the direction of the rail base, which causes the inclined surfaces referred to to ride on one another transversely of the rail base so that the hook spreads slightly, and thus a marked spring pressure is exerted between the contacting surfaces tending to prevent relative movement of the yoke and jaw longitudinally of the rail base.

In the present invention my object is to devise a form of yoke member which may be cut out and shaped in a die press, and which will possess increased longitudinal resiliency over and above the yoke member shown in the hereinbefore mentioned patent, thus increasing the possible range of the relative movement of the yoke, hook and jaw member transverse of the rail and the consequent spring pressure between the contacting surfaces of these parts.

I attain my object by means of the construction hereinafter described and illustrated in the accompanying drawings, in which—

Fig. 1 is a side elevation of my improved rail anchor in position on the base of a rail.

Fig. 2 a rear elevation of the same;

Fig. 3 a plan view; and

Fig. 4 a plan view of a modification of the yoke member.

In the drawings like numerals of reference indicate corresponding parts in the different figures.

1 is a wedge-shaped jaw member adapted to fit over one edge of the rail base. While this jaw member might directly engage a

tie, it is preferably provided with an integral abutment member 2 extending downwardly adapted to engage the side of the tie. 3 is a yoke member formed of suitable resilient material. While it is not essential that what is known as spring steel be employed for this member, it is necessary to employ a steel having a fair measure of resiliency. This yoke member is provided with a hook 4 at one end adapted to engage one edge of a rail base, while the other end is provided with the hook 5 adapted to embrace the jaw member and overhang the rail base as shown particularly in Fig. 1.

In the present invention this yoke member is cut and formed in a die press from an oblong piece of steel plate intermediate of its ends. The yoke member, as it will be seen particularly on reference to Fig. 3, is laterally bent or bowed. This bow may extend towards either side, or a compound curvature might be employed as shown in Fig. 4. The result of this construction is that the yoke member is given a certain amount of longitudinal resiliency, that is to say, forces applied to the hooked ends in opposite directions tend to flatten the bowed portion of the yoke member and to spread the hooks apart, and, as the metal of the yoke member is resilient, spring pressure is exerted by the hooks against any parts with which they may be engaged. It is preferred that the yoke member adjacent the hook 4 should lie close against the under side of the rail base, thence curving downwardly to pass under the lower part of the jaw member. It is preferred that the hooked ends of the yoke member shall extend in substantial alignment with one another as shown. The back of the jaw member is wedged shape, as shown, so that when the jaw member is fitted between the rail base and the hook 5 and the yoke is driven into position, the hook 4 is tightened against one edge of the rail base, and the jaw member 1 against the other edge of the rail base, thus effectively clamping the rail anchor as a whole to the rail base.

As in my prior patent hereinbefore referred to the upper part 6 of the hook 5 has its under surface inclined inwardly and downwardly, and the upper surface of the jaw-shaped member is similarly shaped. As the yoke member is driven into position over the jaw, there is a movement of the hook 5 transversely of the rail base in one

direction, while there is more or less movement of the jaw transversely of the rail base in the opposite direction. This causes the inclined surfaces referred to to ride on one another transversely of the rail base so that the parts of the hook spread slightly and thus a marked spring pressure is exerted between the contacting surfaces. Owing to the longitudinal resiliency of the yoke member, which results from its peculiar construction, considerable movement is possible between the parts and the pressure exerted is considerably greater than is possible with the earlier construction. It will be noted that this wedge action takes place in a direction at right angles to the wedging action of the back of the jaw, so that any component of the force exerted to loosen the engagement does not add to the effect of any component of the force exerted by the back of the wedge tending to loosen the engagement of the wedge.

What I claim as my invention is:—

1. A rail anchor comprising a jaw member adapted to embrace one edge of a rail base and having its back formed as a wedge; and a yoke of spring metal adapted to span the rail base formed with a lateral bend and having a hook at one end adapted to engage one edge of the rail base, and a hook embracing the jaw member and overhanging the rail base, the engaging surfaces of the jaw member and the upper part of said hook sloping inwardly and downwardly in the direction of the rail base.

2. A rail anchor comprising a jaw member adapted to embrace one edge of a rail base and having its back formed as a wedge; and a yoke of spring metal adapted to span the rail base formed with a lateral bend and having a hook at one end adapted to engage one edge of the rail base, and a hook embracing the jaw member and overhanging the rail base, the engaging surfaces of the jaw member and the upper part of said hook being shaped to spread the hook when the hook and jaw member are moved transversely of the rail base, the first outwardly and the latter inwardly.

3. A rail anchor comprising a jaw member adapted to embrace one edge of a rail base and having its back formed as a wedge; and a yoke of spring metal adapted to span the rail base formed with a lateral bend and having a hook at one end adapted to engage one edge of the rail base, and a hook embracing the jaw member and overhanging the rail base, the yoke being adapted to fit close to the under side of the rail base for

a considerable part of its length, thence inclining downwardly and then parallel to the rail base to pass under the jaw member, the engaging surfaces of the jaw member and the upper part of said hook sloping inwardly and downwardly in the direction of the rail base.

4. A rail anchor comprising a jaw member adapted to embrace one edge of a rail base and having its back formed as a wedge; and a yoke of spring metal adapted to span the rail base having a hook at one end adapted to engage one edge of the rail base, and a hook embracing the jaw member and overhanging the rail base, the said yoke member being formed of a metal plate cut to shape and having the part intermediate of its ends laterally bent to give said member longitudinal resiliency.

5. A rail anchor comprising a jaw member adapted to embrace one edge of a rail base and having its back formed as a wedge; and a yoke of spring metal adapted to span the rail base having a hook at one end adapted to engage one edge of the rail base, and a hook embracing the jaw member and overhanging the rail base, the said yoke member being formed of a metal plate cut to shape, the upper edge of the part spanning the rail base being adapted to fit close to the rail base for a considerable part of its length, thence inclining downwardly to pass under the jaw, said part spanning the rail base being laterally bent to give the member longitudinal resiliency.

6. A yoke for a rail anchor formed from an oblong spring metal plate of considerable depth relative to its length and thickness cut out to embrace a rail base and formed with a hook at one end adapted to engage one end of the rail base edge a hook at the other end adapted to engage a rail-engaging jaw member, the part of said member between said hooks being laterally bowed.

7. A yoke for a rail anchor formed from an oblong spring metal plate of considerable depth relative to its length and thickness cut out to embrace a rail base and formed with a hook at one end adapted to engage one end of the rail base edge a hook at the other end adapted to engage a rail-engaging jaw member, the hooked ends lying in substantial alinement while the part of the member between said ends is laterally bowed.

Signed at Toronto, Ontario, this twenty-fifth day of April, 1922.

CHARLES G. ERICSON.
